UNITED STATES PATENT OFFICE.

WILLIAM C. HAMMERSMITH, OF DENVER, COLORADO.

ATTACHMENT FOR PRINTING PRESSES.

Application filed October 27, 1924. Serial No. 746,081.

To all whom it may concern:

Be it known that I, WILLIAM C. HAMMERSMITH, a citizen of the United States, residing at the city and county of Denver, and 5 State of Colorado, have invented certain new and useful Improvements in Attachments for Printing Presses; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

This invention relates to improvements in automatic printing presses and has reference more particularly to an attachment designed to guide the paper in its passage 20 towards the stops and to keep the same from rebounding or being displaced from any other cause.

In the operation of automatic printing presses of every kind, and especially presses 25 employed in multiple color printing where perfect registry is necessary, it is important that the paper shall be properly fed to the grippers on the cylinder; that it shall be held flat and prevented from curling away 30 from the guides and stops. Presses of this type are usually provided with a supporting tongue that projects under and past the stops. These tongues support the paper. Above the supporting tongues there are guide 35 tongues that are spaced a considerable distance from the supporting tongues. The paper, as it is fed, strikes the stops, but often rebounds or curls up so that when it is grasped by the grippers, it is not in the 40 proper position to register, with the result that the machine will either stop or poor work will be done.

I have found that by providing an auxiliary guide tongue of this resilient material, such, for example, as phosphor bronze, locating the same over the supporting tongue and so adjusting it that it will press gently against the latter, the paper will be held against the supporting tongue with sufficient force to prevent its rebound and also to keep it from curling.

My invention can be most clearly explained and will be most readily understood when reference is had to the accompanying drawing, in which my improvement is

shown on a press in its proper relation to the other parts, and in which:

Fig. 1 is a perspective view of a portion of a printing press showing my improvement in place thereon; 60

Fig. 2 is a section taken on line 2—2, Fig. 1;

Fig. 3 is a top plan view of my auxiliary guide finger; and

Fig. 4 is a side view thereof. 65

In the drawing only such portions of the printing press have been shown as are necessary for a proper understanding of my invention. Numerals 5 and 6 represent the sides of the feeder mechanism, numeral 7 70 indicates the cylinder, while numeral 8 designates the mechanism which carries the printed paper away. The sides 5 and 6 are connected by bars which perform various functions, one of which I have designated 75 by the numeral 9. A bar 10 connects the sides 11 and 12 and carries the adjustable stops 13, which have a notch 14 in their lower ends for receiving the supporting tongue 15. The paper sheet 16 rests on the 80 supporting tongues 15 and abuts the stops 13. Presses of this type are usually provided with guide tongues or fingers 17 which are spaced a short distance from the top of the supporting tongues 15. These guide tongues 85 are of very little value in guiding the paper, as they are spaced from the tongues 15 a distance greater than the thickness of the paper, which, therefore, never contacts therewith unless the paper bulges up for 90 some reason or another. To prevent the edge of the paper from curling up, the stops 13 have been provided with curved members 117 whose function it is to hold the edge of the sheet against the top of the 95 supporting finger 15. It was found that with the equipment described the paper will sometimes rebound from the stops or curl upward and move out of its proper position sufficiently to destroy the proper 100 register and produce defective work.

In order to overcome this difficulty, I provide an auxiliary guide tongue 18 above each of the supporting tongues 15. These auxiliary guide tongues are made of thin 105 resilient material, such, for example, as phosphor bronze, spring brass, or German silver,—in fact, any material suitable for this purpose may be used. One end of the tongue 18 is fastened to a clamp comprising 110

two members 19 and 20, being fastened between the straight portions of these clamps. The clamps have curved ends 21 and 22 which embrace the rod 9 and are so dimensioned that they will grip the rod with sufficient force to prevent rotation. The clamp member 20 has a longer straight portion than the member 19 and is provided at its end with an adjusting screw 23 by means 19 of which the tongue 18 may be forced against the supporting tongue 15 with greater or less pressure. The tongues 18 terminate in close proximity to the stop 13, and are of such strength and so adjusted 15 that they will permit the sheet 16 to move up against the stops 13. It is evident that the tongues 18 will hold the sheet of paper flat and prevent it from rebounding after it has struck the stop. In fact, when a 20 press is equipped with my auxiliary tongue, the paper will stay where it belongs until grasped by the grippers 24. This permits the press to be speeded up and prevents stops due to misplaced paper as well as damage due to defective work.

Having now described my invention, what I claim as new is:

1. In a printing press, in combination, a 30 rotating cylinder provided with gripping devices, means for feeding sheets of paper to said cylinder, means for guiding the paper into position to be engaged by the grippers, said guide means comprising a tongue adapted to support a sheet of paper, a stop 35 mechanism operatively associated with said tongue for stopping a sheet of paper in proper position to be engaged by the grippers, and a resilient tongue secured at one end to a fixed support and located above the 40 first-mentioned tongue, said resilient tongue being adapted and adjusted to exert a yielding pressure on the upper side of a sheet of paper as it is fed toward said stops for the 45 purpose of holding it against the supporting tongue.

2. In a printing press, in combination, a 50 rotating cylinder provided with gripping devices, means for feeding sheets of paper to said cylinder, means for guiding the paper into position to be engaged by the grippers, said guide means comprising a tongue adapted to support a sheet of paper, a stop

mechanism operatively associated with said tongue for stopping a sheet of paper in proper position to be engaged by the grippers, a resilient tongue secured at one end to a fixed support and located above the 55 first-mentioned tongue, said resilient tongue being adapted and adjusted to exert a yielding pressure on the upper side of a sheet of paper as it is fed towards said stops for the purpose of holding it against the supporting tongue, and means for adjusting the pressure exerted by the auxiliary tongue.

3. In a printing press, in combination, a 60 rotating cylinder provided with gripping devices, means for feeding sheets of paper to said cylinder, means for guiding the paper into position to be engaged by the grippers, said guide means comprising a tongue 70 adapted to support a sheet of paper, a stop mechanism operatively associated with said tongue for stopping a sheet of paper in proper position to be engaged by the grippers, a resilient tongue located above the 75 first-mentioned tongue, said resilient tongue being adapted to exert a pressure on the upper side of a sheet of paper for the purpose of holding it against the supporting tongue, and means for adjusting the pressure exerted by the auxiliary tongue, said means comprising a screw threadedly connected to a 80 bracket and having its end in contact with the resilient tongue.

4. In a printing press, in combination, a 85 rotating cylinder provided with gripping devices, means for feeding sheets of paper to said cylinder, means for guiding the paper into position to be engaged by the grippers, said guide means comprising a tongue 90 adapted to support a sheet of paper, a stop mechanism operatively associated with said tongue for stopping a sheet of paper in proper position to be engaged by the grippers, and means located above and normally contacting with the upper surface of the 95 guide tongue for preventing the paper from rebounding and curling, said means comprising a flat strip of resilient material having one end anchored to the press frame and the other end resting on the guide tongue.

In testimony whereof I affix my signature.

WILLIAM C. HAMMERSMITH.
